UNITED STATES PATENT OFFICE

133,435

DESIGN FOR A DISPLAY TABLE

Robert Jay Gunder, Manor Township, Lancaster County, Pa., assignor to Hamilton Watch Company, Lancaster, Pa.

Application April 22, 1942, Serial No. 106,653

Term of patent 14 years

To all whom it may concern:

Be it known that I, Robert Jay Gunder, a citizen of the United States, residing in Manor Township, in the county of Lancaster, and State of Pennsylvania, have invented a new, original, and ornamental Design for a Display Table, of which the following is a specification, reference being had to the accompanying drawing, forming part thereof.

The figure is a perspective view of a display table, showing my new design.

I claim:

The ornamental design for a display table, as shown.

ROBERT JAY GUNDER.
